UNITED STATES PATENT OFFICE

103,431

DESIGN FOR A BRAID OR SIMILAR ARTICLE

Hugo Mehler, Buny-Hut Farms, Pa.

Application January 16, 1937, Serial No. 67,087

Term of patent 7 years

To all whom it may concern:

Be it known that I, Hugo Mehler, a citizen of the United States, residing at Buny-Hut Farms, in the county of Bucks and Commonwealth of Pennsylvania, have invented a new, original, and ornamental Design for Braid or Similar Article, of which the following is a specification, reference being had to the accompanying drawing, forming a part thereof.

The figure is a plan view of the braid embodying the design of this invention.

I claim:

The ornamental design for a braid or similar article, as shown.

HUGO MEHLER.
